Des. 236,747
Patented Sept. 9, 1975

236,747

CANDLE HOLDING SCONCE OR THE LIKE

James D. M. Green, 38 Neck Road, Ponte Vedra Beach,
Fla. 32082, and Tom R. Turner, Jr., 4614 Rosemont
Road, Jacksonville, Fla. 32207

Filed Dec. 12, 1973, Ser. No. 424,108

Term of patent 14 years

Int. Cl. D26—01

U.S. Cl. D48—2

FIG. 1

FIG. 2

FIG. 3

FIG. 4

FIG. 1 is a front elevational view of a candle holding sconce or the like showing our new design;

FIG. 2 is a right side elevational view thereof;

FIG. 3 is a top plan view thereof; an opening through the top portion of the cylinder being partially blocked by the rearwardly extending top spire; and

FIG. 4 is a rear view thereof.

We claim:

The ornamental design for a candle holding sconce or the like, substantially as shown and described.
